(57) CLAIM

The ornamental design for a golf shoe with sole profile, as shown and described.

DESCRIPTION

FIG. 1 is a perspective view of the golf shoe upper showing our new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The crescent shaped broken lines in FIGS. 1, 3, 4, and 6, form no part of the claim.

The broken line showing of the sole is for illustrative purposes only and forms no part of the claimed design.
